UNITED STATES PATENT OFFICE.

ANDREW C. BOLTON, OF NEW YORK, N. Y., ASSIGNOR TO GUTTA PERCHA & RUBBER MANUFACTURING COMPANY, OF NEW YORK, N. Y., A CORPORATION OF NEW YORK.

WRAPPING-MACHINE.

1,099,535.

Specification of Letters Patent.

Patented June 9, 1914.

Application filed April 9, 1909. Serial No. 488,954.

To all whom it may concern:

Be it known that I, ANDREW C. BOLTON, a citizen of the United States, and resident of the borough of Brooklyn, county of Kings, city and State of New York, have invented 5 certain new and useful Improvements in Wrapping-Machines, of which the following is a specification.

My invention relates to wrapping machines and more particularly to machines for wrapping hose with fabric while the rubber is in a green state and prior to vulcanizing and has for its object to provide a machine of this character which is simple in construction and easy of operation. Heretofore in 10 many instances, it has been customary to wrap hose in this manner by hand, resulting in great unevenness of wrapping and tension and also in a great expenditure of time. 15 My invention is intended to overcome these difficulties and to wrap the hose evenly and to apply the fabric under a uniform and even tension. In wrapping hose by hand it is necessary to place the hose on a mandrel so 20 as to enable the hose to be properly manipulated. With my machine if desired the use of the mandrel may be omitted and during the curing operation the hose may be filled with air under pressure by means of suitable 25 mechanism. My machine may also be used for unwrapping the fabric from the hose after it has been cured.

Other objects of my invention will appear from the description hereinafter and the 30 features of novelty will be pointed out in the appended claims.

Reference is to be had to the accompanying drawings in which—

Figure 1 is a side elevation of my improved machine; Fig. 2 is a cross section thereof on the line 2—2 of Fig. 1; Figs. 3 and 3^a are horizontal sections on the line 3—3 of Fig. 1; Figs. 4 and 4^a are sectional views on the line 4—4 of Figs. 3 and 3^a; Fig. 45 5 is a sectional view on the line 5—5 of Fig. 1; Fig. 6 is a sectional view on the line 6—6 of Fig. 3^a; Fig. 7 is a detail sectional view of one of the feed tube ends; Fig. 8 is a cross section thereof on the line 8—8 of Fig. 7; Fig. 9 is an elevation partly in section of the 50 opposite end of the feed tube; Fig. 10 is an end view thereof; Figs. 11, 12 and 13 are diagrammatic views in cross section showing the longitudinal wrapping at different steps of the winding operation and Fig. 14

is an elevation of the hose after it has been wrapped.

A is a support on the upper end of which is located the journal box B in which the tubular shaft C is arranged to rotate. D is 60 a gear wheel secured to said shaft C to rotate therewith and which meshes with a gear wheel E carried by the driving shaft E'. This driving shaft E' is journaled in a bearing A' on the frame A and a support A² 65 and has mounted thereon the fast pulley F and the loose pulley F'. The shaft E' further carries the pinion G which meshes with a gear wheel G' journaled on a stud G² secured to the frame A, which wheel G' in 70 turn engages a pinion H. The pinion H is mounted on a shaft H' journaled in bearings H² and H³, on which shaft H' is also located a worm gear H⁴. The said worm gear H⁴ is located between and meshes with worm 75 wheels I, I' secured to the lower ends respectively of upright shafts I², I³. The shafts I² and I³ are mounted to rotate in bearings I⁴ secured to a stationary support I⁶ and carry at their upper ends, the feed rollers 80 I⁷ and I⁸. These feed rollers are made with concave peripheries and if desired may be covered with rubber or similar material to prevent laceration of the hose and to insure a better gripping action. 85

A stationary feed tube or guide J is supported and clamped against rotation in a bearing J' carried by an arm J² which is secured to the frame A. The said tube J extends through and beyond the tubular shaft 90 C and is provided at one end with a removable split bushing J³ the purpose of which will be more fully described hereinafter. The tubular shaft C has secured to its one end a removable collar C' fastened in position by means of a clamp nut C². This collar C' is formed with a reduced tubular portion C³ arranged in axial alinement with the feed tube J and having an internal diameter corresponding to the internal diameter of 95 the bushing J³. The said reduced portion C³ is slotted lengthwise as indicated at C⁴ and is formed with a projection C⁵ extending outwardly therefrom adjacent to the slot C⁴.

K is an arm secured to the tubular shaft C 100 to rotate therewith and carries a short wrapper guide K'. The said arm is weighted as indicated at K² and further has the inner end of a second wrapper guide K³ secured thereto which guide K³ extends at an angle 110

from the said arm and has its outer end in close proximity to the projection C⁵ of the collar C'. The guide K³ is provided throughout a portion of its extent with 5 spaced cross pins K⁴ under and over which the fabric passes from the solid portion K⁵ of the wrapper guide K³. The outer end of the said guide K³ is also secured to the tubular shaft C as indicated at K⁶. A reel L is 10 loosely mounted on the tubular shaft C between the arm K and a collar L' secured against movement on said shaft C by a set screw L² and is arranged to contain the supply of fabric L³ with which the hose is to be 15 wrapped spirally.

A standard M is secured to the support A² and has secured to it near its free end a bearing M' for the bevel pinion M². This bevel pinion M² is provided with an annular 20 groove M³ into which extends a pin M⁴ to maintain said bevel gear in position against vertical movement while permitting free rotation thereof. A spindle N' extends through said bevel pinion M² and is keyed 25 thereto by means of a spline N². The spindle N' carries at its upper end the wrapping disk N which is provided with bristles N³ arranged to engage and wrap the fabric about the hose. The lower end of said spindle N' engages and is supported by a washer N⁴ located above an adjusting screw N⁵ having a screw thread engagement with the bearing M'. Hook-like members N⁶ are secured adjustably to lugs N⁷ carried by the 30 support A². The members N⁶ are provided with slots N⁸ and are fastened in their adjusted position by screws N⁹ and further extend over the hose to hold it against rising when the wrapping disk N is operated. A 35 short shaft N¹⁰ is journaled in a bearing N¹¹ secured to the standard M and carries a bevel gear N¹² in mesh with the bevel pinion M² and also carries a sprocket or belt wheel N¹³. This sprocket or belt wheel N¹³ is connected by means of a sprocket chain or belt 40 N¹⁴ with a similar sprocket or belt wheel N¹⁵ secured to the power shaft E'. The wrapping disk N is so located as to have its center in a vertical plane corresponding to the 45 axis of the shaft C. A trough O is secured on a support A³ beneath another trough O' located at a distance above the trough O which trough O' has rotatably mounted thereon a reel O² arranged to carry the fabric O³ which is wrapped about the hose longitudinally. The trough O' contains a liquid and is mounted on standards O⁴ and O⁵ secured respectively to the support A³ and the trough O. Rollers P and P' are 50 mounted between the standards O⁴ near opposite ends thereof and spaced rods P² extend from one standard O⁴ to the other between the said rollers P and P'.

Q is a curved guard having its ends secured to opposite sides of the support A and

carrying the screening Q'. The said guard and screening are located adjacent to the arm K and are intended as a protection for the operator against injury by the arm K as it travels around.

In operation the hose R in its green state is passed over the wrapping disk N and the fabric O³ is passed over the roll P and then in and out over the rods P² and is drawn under the roll P' up to the disk N. The said fabric is then placed on the hose over which it hangs in the shape of an inverted U as shown in Fig. 11 and is maintained in position by the members N⁶. This fabric is now wrapped longitudinally about the hose by hand and the wrapped hose is then inserted into the tube J and pushed through until the end thereof projects through the said tube. This projecting end with the fabric O³ thereon is then wrapped spirally by hand with the fabric L³ for a short distance or until the end of the hose enters the space between the rollers I¹ and I². If the machine is now started the rollers I¹ and I² will draw the hose along through the tube J which thus serves as a guide therefor. As the hose is thus drawn along the disk N will also be rotated by means of the sprockets N¹³, N¹⁵ and the chain N¹⁴. The fabric O³ is meantime also drawn along and the one portion 1 thereof is folded or wrapped under the hose as shown diagrammatically in Fig. 12, by means of the part of the bristles N³ which travel in the direction of the arrow 2 in Fig. 3^a. As the hose now continues in its travel and as the portion 3 of the fabric O³ reaches the part of the bristles N³ which rotates in the opposite direction as indicated by the arrow 4 in Fig. 3^a this portion 3 will be folded or wrapped under the hose and over the end of the portion 1 as shown in Fig. 13. It is to be understood that the fabric O³ is maintained in a moist condition by a liquid, preferably water, in the trough O' and for that reason adheres to the outer surface of the hose. Owing to the fact that the bristles N³ are flexible and the upper ends thereof are located in a plane slightly higher than the lower part of the hose, the said bristles will be bent on passing under the hose and will exert a sweeping action on the fabric as they return to their normal position, thus wrapping it securely about the hose and smoothing out any wrinkles which may occur. During this operation the hose with this first longitudinal wrapping O³ is gradually advancing and as it leaves the end of the tube J is spirally wrapped with the second wrapping L³ in the following manner. As power is applied to the shaft E' the gear E will be rotated and will consequently rotate the gear D and with it the tubular shaft C. Owing to the fact that the arm K is secured to said shaft C, the rotation thereof will cause the end of said arm 125

K to travel in a circular path in the direction indicated by the arrow 5 in Fig. 2. This rotation of the arm will cause the fabric L^s to be wrapped about the hose and owing to the fact that the hose is being fed along this wrapping L^s will be spirally applied over the longitudinal wrapping O^s. The fabric L^s passes from the reel L under the guide K' around the free end of said arm K and over the solid portion K^s of the guide K^s. From this solid portion K^s of the guide K^s the fabric passes under and over the cross pins K⁴ and finally over the projection C^s through the slot C^s to the hose. The pins K⁴ serve to keep the fabric under a slight tension so as to insure a secure wrapping thereof about the hose. This fabric L^s is also preferably applied to the hose in a moist state as in this condition the fabric adheres to the wrapping O^s and is also easier to manipulate and smooth out. It is to be understood that the feed rollers I' and I^s are rotated at a speed to feed the hose in the required manner to properly wrap the hose spirally and longitudinally. The feed rollers I' and I^s are operated through the medium of the worm wheels I and I' and the worm H' on the shaft H'. The shaft H' is rotated by means of the gear H, the gear G' and the pinion G which is mounted on the driving shaft E'. If the hose to be wrapped is of smaller diameter than the tube J, the bushing J² and collar C having an inside diameter slightly larger than the outside diameter of the hose are substituted for the bushing and collar used before. By having bushings and collars of varying sizes all diameters of hose up to the diameter of the tube J can be accommodated.

40 After the preliminary wrapping has been effected by hand and the machine is started it will continue to operate indefinitely, it being understood that each new length of hose to be wrapped is attached to the end of the preceding length of hose and drawn along thereby. The wrappers are cut when it is desired to separate the lengths of hose. With my machine both wrappings are automatically, uniformly and quickly applied under an even tension and without wrinkles.

45 Various modifications may be made without departing from the nature of my invention as defined in the claims.

I claim as my invention:

55 1. A machine for wrapping cylindrical articles comprising a stationary tubular guide for the article, a rotatable tubular shaft surrounding said guide and having a reduced tubular portion spaced from the one end of said guide in axial alignment therewith, said reduced tubular portion being provided with a longitudinally extending aperture of a length corresponding approximately to the axial length of said reduced portion, a radially extending shelf

like projection on said reduced portion adjacent to said aperture and extending substantially from one end thereof to the other, whereby the wrapper is guided to the aperture and through the same to the article and a device carried by said rotatable shaft for guiding the wrapper to the said projection. 70

2. A machine for wrapping cylindrical articles comprising a support for the article, means capable of being rotated in a substantially horizontal plane to wind one wrapper in a predetermined manner on said article, another means capable of being rotated in a substantially vertical plane to wind a second wrapper in a different predetermined manner on the said article and mechanism for rotating each of said means. 75

3. A machine for wrapping cylindrical articles comprising a tubular support for the article, a rotatable brush located adjacent to one end of said tubular support and movable in a substantially horizontal plane for applying a wrapper to the article, an arm movable in a substantially vertical plane for applying a second wrapper to said article, means for feeding said article lengthwise of said support and a guide extending at an angle from said arm to a point adjacent to the other end of said support for guiding said second wrapper to the article. 80

4. A machine for wrapping cylindrical articles comprising a tubular support for said article, removable means at each end of said support for accommodating articles of different diameters, a brush at one end of said support rotatable in a substantially horizontal plane for applying one wrapper to said article, an arm movable in a substantially vertical plane for applying a second wrapper to said article, a guide on said arm 100 extending to a point adjacent to the outlet end of said guide for guiding said second wrapper to the article and means for feeding said article lengthwise of the support. 105

5. A machine for wrapping cylindrical articles comprising a tubular support for the article, a brush adjacent to one end of said support and movable in a substantially horizontal plane for applying one wrapper to said article, a tubular shaft mounted on said support so as to be rotatable about the axis thereof, a carrier for a second wrapper located on said shaft, an arm secured to said tubular shaft to move therewith for applying said second wrapper to said article, and a guide carried by said arm and extending to a point adjacent to the outlet end of said support for guiding said second wrapper from its carrier to the article. 115

6. A machine for wrapping cylindrical articles comprising a stationary support for the article, a carrier for one wrapper, means on said carrier for moistening said wrapper, a brush rotatable in a horizontal plane for applying said wrapper to the article, a tu- 120 125 130

4
bular shaft rotatable about the axis of said support, an arm carried by said shaft for applying a second wrapper to said article, a carrier for said second wrapper located on said shaft and means carried on said arm for guiding said second wrapper to the article.

In testimony whereof I have hereunto set

my hand and seal in the presence of two
subscribing witnesses this 6th day of April
1909.

ANDREW C. BOLTON.
